SUPPORT FOR URINE SPECIMEN CONTAINER OR SIMILAR ARTICLE

Louis Guss, 59 Sachem St., Norwich, Conn.

Filed Aug. 7, 1962, Ser. No. 71,203

Term of patent 14 years

(Cl. D83—1)

FIGURE 1 is a perspective view of a support for urine specimen container or similar article, showing my new design;

I claim:

The ornamental design for a support for urine specimen container or similar article, as shown.
